Putnam Paul Bell

UNITED STATES PATENT OFFICE.

FERGUS A. BUTLER, OF DANVERS, MASSACHUSETTS.

FABRIC.

1,315,179.

Specification of Letters Patent. Patented Sept. 2, 1919.

Application filed March 16, 1916. Serial No. 84,699.

To all whom it may concern:

Be it known that I, FERGUS A. BUTLER, a citizen of the United States, residing at Danvers, in the county of Essex and State 5 of Massachusetts, have invented certain Improvements in Fabrics, of which the following description, in connection with the accompanying drawings, is a specification, like reference characters on the drawings indicating like parts in the several figures.

This invention relates to garments, blankets, robes, and similar articles of apparel designed to protect the wearer or user from cold and to a novel material from which 15 to make articles of this character. The invention has for its object to devise an article of this character and a material for use in such articles which will be relatively light in weight and yet shall possess unusual heat 20 insulating properties. It is proposed to utilize the heat insulating properties of air in attaining this object and to make provision for preventing a sufficient circulation of the air so used to reduce materially its insulating 25 properties.

The invention will be readily understood from the following description of one embodiment thereof, reference being made to the accompanying drawings, in which—

30 Figure 1 is a perspective view of a garment made in accordance with this invention, and

Fig. 2 is a cross-sectional view of the fabric from which the garment shown in Fig. 35 1 is made.

Referring particularly to Fig. 2 it will be seen that the fabric from which the garment is made consists of an outer covering 2 and a lining 4 with several layers of material between the covering and lining. These layers consist of sheets 6 of air retaining material of some convenient character alternating with sheets 8 of material substantially impervious to the passage of air. It is obvious 40 that the exact materials used will vary with the requirements of the service to which the garment or other article is to be put; but the fundamental idea is to make, by means of suitable sheets of substantially impervious material, a series of air spaces which will give to the article, whether it be a fabric, garment, blanket or the like, the desired 45 heat insulating properties.

The sheet material 8 need not of course be 50 absolutely impervious to the passage of air but should be substantially so in order to

prevent any material interchange of air in the spaces between adjacent sheets. It is obvious that a free interchange of air in these spaces would totally defeat the object in view. For this material a large variety of substances may be used. For many purposes some of the tough grades of paper on the market are satisfactory; and where the article is to be put to very severe service 60 some of the animal tissues, such as sheep-skin or sheets of the cured intestines of animals may be used. A thin grade of sheet rubber of good quality which does not harden when subjected to low temperatures 65 also may be used.

The sheets of material 6 that separate the sheets 8 may also vary widely in character. The primary purpose of this material is to separate the sheets 8 so as to maintain an 70 air space at all times between any two adjacent sheets of the relatively impervious material. Any one of a large variety of woven or knitted fabrics made either of cotton or wool will answer for this purpose, 75 although wool is usually preferable because it is a better heat insulator and the wool fibers do not mat together as do cotton fibers. Cotton, however, is satisfactory for many purposes; and either of these materials will retain sufficient air to form good 80 heat insulators. It is obvious that the particular kind of heat insulating and impervious material used in any article will have to be determined by the demands of the service required from that article. The number 85 and thickness of the air spaces provided will depend also upon the purposes to which the article is to be put. If paper is used for the impervious material, the air retaining fabric 90 used with it will be depended upon for mechanical strength and the sheets 6 and 8 should be sewed together at suitable intervals, as indicated at 9, Fig. 1, a strip of tape 95 10 being used on the side of each paper sheet 100 8 opposite the fabric 6 to receive the stitches and prevent them from cutting through the paper. Preferably also the paper is crinkled in order to make it more pliable and to reduce the strain on the paper where it is 105 stitched and thus prevent it from tearing. In the manufacture of robes, blankets, and similar coverings it may be desirable to sew together, or unite by some other means, all the sheets 6 and 8 between the lining and 110 the outer covering and to secure them to the lining and covering in such a manner as by

buttons and buttonholes, so that they can readily be removed, thus permitting the washing of the sheets 2 and 4 which are exposed to wear and are very likely to become soiled.

The materials used for the outer covering 2 and the lining 4 must of course be selected according to the nature of the service required from the article. For many purposes, such for instance in garments and blankets it probably will be preferable to use for the outer covering a waterproof material of some character, such for instance, as gabardine, although the more common fabrics used for these purposes may also be employed here. It will be unnecessary, however, to use as heavy a fabric as that ordinarily employed because the warmth of the article will not depend primarily upon this outer fabric, as in articles of apparel constructed in accordance with more common methods, but rather upon the materials between this outer covering and the lining and the number and thickness of the air spaces so provided. For many articles one of the sheets 6 or 8 probably will form the lining of the outer covering. For instance, in making vests, the materials naturally selected for the sheets 6 or 8 would be suitable also for the lining or for the outer covering.

It is obvious that the exact materials used for the several parts of a fabric made up in the manner above described can not be specified exactly because they must be selected, as above stated in accordance with the requirements of the service to which the article is to be put. Accordingly, it will readily be appreciated that the invention is not limited to the use of any specific materials, but

that the present disclosure is directed particularly to such an explanation of the underlying principles of the invention as will enable others to practice the invention successfully.

45

Having thus described my invention, what I claim as new and desire to secure by Letters Patent of the United States is:

1. A pliable fabric from which to manufacture garments, blankets and the like, comprising a series of pliable parallel sheets of material substantially impervious to the passage of air, a sheet of air retaining material between each two of the adjacent sheets of said impervious material, and a separate uniting agent securing all of said sheets together. 50

2. A pliable fabric from which to manufacture garments, blankets and the like, comprising a series of pliable parallel sheets of material substantially impervious to the passage of air, a sheet of air retaining material between each two of the adjacent sheets of said impervious material, and additional means for uniting all of said sheets together 60 at intervals. 65

3. A pliable fabric from which to manufacture garments, blankets and the like, having an outer covering, a lining, a series of pliable parallel sheets of material substantially impervious to the passage of air, a sheet of air retaining material between each two of the adjacent sheets of said impervious material, and means additional to said sheets for securing said sheets of impervious material and air retaining material together. 70 75

In testimony whereof I have signed my name to this specification.

FERGUS A. BUTLER.
